UNITED STATES PATENT OFFICE.

AUGUST B. WITTMANN AND GEORGE L. RORK, OF DENVER, COLORADO.

ROCK-DRILLING EXPLOSIVE-ENGINE.

No. 890,546.

Specification of Letters Patent.

Patented June 9, 1908.

Application filed January 29, 1906. Serial No. 298,425.

To all whom it may concern:

Be it known that we, AUGUST B. WITTMANN and GEORGE L. RORK, both citizens of the United States, residing in the city and county of Denver and State of Colorado, have invented certain new and useful Improvements in Rock-Drilling Explosive-Engines; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to improvements in rock drills in which the reciprocating device acting on the operating tool or drill steel, is actuated by explosive force acting alternately in opposite ends of the piston chamber.

In our improved device a piston is mounted on the stem of the reciprocating hammer, and acts in a chamber whereby the explosive mixture is controlled and introduced to the chamber in which the hammer or other reciprocating device is operated.

Having briefly outlined our improved construction, we will proceed to describe the same in detail reference being made to the accompanying drawing in which is illustrated an embodiment thereof.

In this drawing, Figure 1 is a top plan view of a drill equipped with our improvements. Fig. 2 is a side elevation of the same. Fig. 3 is a vertical longitudinal section shown on a larger scale and with parts broken away. Fig. 4 is a fragmentary sectional view taken vertically through the structure for controlling the supply of explosive mixture to the explosion chamber, parts being shown on a much larger scale. Fig. 5 is a horizontal section taken through the explosion chamber and the parts immediately forward thereof. Figs. 6 and 7 are sections taken on the lines 6-6 and 7-7 respectively, of Fig. 4. Fig. 8 is an enlarged sectional view in detail showing the construction of the sparking plugs.

50 The same reference characters indicate the same parts in all the views.

Let the numeral 5 designate the ordinary guide shell of a rock drill structure. Slidably mounted in this guide shell is a base 55 plate 6 upon which the body of the machine is mounted. This body portion of the ma-

chine includes an explosion chamber or barrel 7 in which is located a reciprocable hammer or hammer head 8 connected with a rod 9 which passes through a stuffing box 10 at 60 one extremity of the chamber. In direct alinement with the explosion chamber 7 is a piston chamber 12 through which the hammer stem 9 passes. Within this chamber is located a piston 13 made fast to the stem 9 65 and mounted to reciprocate within the chamber 12. The chamber 12 is located between buffer heads 14 and 15 which are acted on by springs 17 and 18. These heads yield sufficiently to prevent injury to the parts as the 70 piston reaches the extremities of its chamber. The gland of a stuffing box 19 is located in a recess formed in the buffer head 14. This gland is suitably connected with the body part of the device.

Mounted upon the body of the structure adjacent the chamber 12 is a chamber 20 which receives the explosive mixture through a port 21. In the extremities of this chamber are formed ports 22 communicating with 80 exit openings 23 which are surrounded by valve seats 24. These valve seats are engaged by valves 25 and 26 having stems 27 and 28 passing through the heads of the chamber and normally held in the closed position by springs 29. At opposite ends of the chamber 20 are located chambers 30 and 31 whose outer extremities are closed by screw plugs 32 and 33. The extremities of these chambers adjacent the chamber 20, are 90 provided with openings normally closed by valves 34 and 35 having stems 36 and 37 recessed to receive coil springs 38 and 39 which normally hold the valves in the closed position. These valves 34 and 35 open inwardly 95 while the valves 25 and 26 open outwardly. The valves 26 and 34 are oppositely located and when closed there is a narrow passage way 40 between them. There is also a similar passage way 41 between the valves 25 and 100 35 when both of the last named valves are closed. These passages 40 and 41 communicate with the opposite extremities of the chamber 12.

As the piston 13 moves toward the left referring to Figs. 3 and 4, the valve 26 will open in response to the vacuum produced in the chamber 12 and allow the explosive mixture to enter the last named chamber at the right of the piston. At the same time the 110 explosive mixture in the chamber 12 at the left of the piston will be forced out through

the passageway 41 and through the opening controlled by the valve 35 and thence through a port 42 into a branch pipe 43 and thence into a main conduit 44 whence it is delivered to a chamber 45 and enters the explosion chamber at the right of the hammer 8 (see Fig. 5). Again as the piston 13 moves toward the right in the chamber 12, the explosive mixture is forced out of the last named chamber through the narrow passage 40, thence through the opening controlled by the valve 34, into the chamber 30 and thence through a port 47 into a branch pipe 48, and thence into the main conduit 44. From this conduit 44 the explosive mixture passes again to the chamber 45 and thence through a duct 48 to the left of the hammer 8 (see Fig. 5).

It is evident that during the reciprocation of the piston 13, the hammer 8 is also reciprocated. As this hammer moves toward the right, the explosive mixture introduced to the explosion chamber 7 as aforesaid, is compressed in the right hand extremity of the chamber and is ignited through the instrumentality of a sparking plug 49 of special construction. The explosive force acting on the hammer at its right hand extremity, drives it toward the left whereby the explosive mixture is compressed in the left hand extremity of the chamber 7 where it is in turn ignited through the instrumentality of a sparking plug 50. In this way the reciprocating movement of the hammer is effected.

Each sparking plug 49 or 50 is composed of a screw sleeve A, a central electrode B passing through the center of the sleeve and separated therefrom by insulating material C. A circuit wire D is fastened to the outer exposed extremity of the electrode B by a screw button E threaded into the outer or exposed extremity of the electrode. The electrode B protrudes into the explosion chamber and its inner extremity is slightly separated from a projection F connected with the sleeve A.

From one pole of an electrical source G, a conductor H leads to the body part of the structure. From the other pole of the source a wire I leads to a contact J. From this wire I leads a branch conductor K to a contact L. The contacts L and J are separated from each other by an insulating member M upon which the contacts are mounted. Connected with the contact J is a rearwardly projecting metal brush N; while connected with the contact L is a forwardly projecting metal brush O. Opposite the contacts J and L are two contacts P and Q provided with metal brushes R and S which extend rearwardly and forwardly, respectively. These brushes and contacts are located in the rear of the body of the machine. A stem T in alignment with the hammer stem 9 and connected with the piston 13, protrudes from the body of the machine and

carries a contact ring U insulated from the stem as shown at V. When the piston 13 and the hammer 8 are at their rearward limit of movement or have reached their limit of travel toward the right, the ring Q 70 engages the two brushes N and R, and conducts the current from the source through a conductor D to the electrode B of the sparking plugs 49. The circuit is completed after making the spark within the chamber, 75 through the metal body or frame of the machine back to the opposite pole to the supply source G, through the wire H. On the other hand when the piston 13 and the hammer 8 are at their forward limit of movement or 80 at their limit of travel toward the left referring to Figs. 4 and 5, the contact ring U will reach the dotted line position in Fig. 2 and bridge the space between the brushes O and S, carrying the current to a conductor D' and, 85 thence through the electrode of the sparking plug 50, the circuit being completed in the manner just explained.

At the time the hammer reaches its forward limit of movement it strikes a tappet or anvil 51 which engages the drill steel 52. As shown in the drawing a spring 53 is employed to maintain the steel and the tappet normally at their rearward limit of movement. This spring acts on a collar 54 formed on the 95 drill steel when the latter engages the forward enlarged extremity 51^a of the tappet.

When the hammer is at its forward limit of movement, the products of combustion in the rear escape through exhaust ports 55 and 56 to the chamber 57 and thence through a port 58 to the atmosphere or any desired location in case it is desired to connect a conduit (not shown) with the port 58 which is interiorly threaded for the purpose. This 100 exhaust occurs simultaneously with the entrance of a part of the explosive mixture through the port 46 to the explosion chamber in the rear of the hammer. Now when the explosion occurs forward of the hammer, and 105 the latter begins its rearward or return stroke, the exhaust port 56 will be first closed at which time a small part of the port 46 will be open for the admission of the mixture. In another instant the inlet duct 110 or port 46 is completely cut off from communication with the explosion chamber. The exhaust port 55, however, is still open. As 115 soon as this port 55 is closed compression in the rear extremity of the explosion chamber 120 commences. Again just before the hammer reaches its rearward limit of movement an exhaust port 59 is opened for the escape of the products of combustion forward of the hammer. The inlet port 48 and the exhaust 125 port 60 are then opened allowing a part of the explosive mixture to enter the explosion chamber forward of the hammer simultaneously with the period of exhaust of the products of combustion from the forward extrem- 130

ity of the explosion chamber. The walls of the body of the structure are provided with a suitable number of chambers for the circulation of cooling water. As there is nothing new about these features they need not be described in detail. These chambers are indicated at 61 in Figs. 3 and 5 of the drawing.

From the foregoing description the use and operation of our improved rock drilling

10 explosion engine will be readily understood. Assuming that the hammer or hammer head

is at its rearward limit of movement as shown

in Fig. 3 of the drawing, and that the explosive

15 mixture is compressed in the rear extremity of the explosion chamber or barrel,

the sparking circuit will be closed as heretofore explained resulting in the ignition of the

15 compressed gas, whereby the hammer is

driven forwardly against the tappet or anvil

20 51. Simultaneously with the arrival of the

hammer at its forward limit of movement,

the explosive mixture will be ignited at the

25 forward extremity of the explosion chamber

by virtue of the construction and arrangement

25 of parts heretofore described. The

force of the explosion will drive the hammer

rearwardly when the operation heretofore

described will be repeated. Simultaneously

30 with the movement of the hammer just de-

scribed, the piston 13 is reciprocated and the

explosive mixture taken into the chamber 12

and alternately driven from the opposite extre-

35 mities thereof into the explosion chamber

in the manner heretofore explained more in

35 detail.

The explosion chamber is provided with

lubricating material through the instrumen-

tality of an oil cup 62 having a tubular stem

63 which communicates with the explosion

40 chamber at a central point whereby as the

hammer reciprocates the lubricant deliv-

ered to the chamber is distributed.

Attention is called to the fact that the

tappet 51 passes through a stuffing box 64

45 located forward of the front end of the ex-

plosion chamber. The gland of this stuffing

box prevents the escape of the explosive

50 mixture around the tappet.

The term "explosion chamber" and "bar-

55 rel" are used interchangeably in the specifi-

cation when referring to the element 7; the

terms "hammer" and "hammer head" are

both used to designate the element 8; while

55 the terms "tappet" and "anvil" are used

interchangeably to designate the element

51; and wherever either interchangeable

term is employed alone, the other is equally

applicable.

Having thus described our invention,

60 what we claim is:

1. In a rock drilling explosive engine, the

combination of an explosion chamber, a

hammer therein, means for producing explo-

65 sions automatically in the opposite ends of

the explosion chamber, whereby the explo-

sive force is caused to act on the hammer from both extremities of its chamber, a piston connected to move in unison with the hammer, a chamber in which said piston reciprocates, valve mechanism co-operating 70 with the piston whereby the explosive mixture is drawn into the piston chamber, and expelled therefrom during the reciprocation of the said piston, and suitable means for conducting the expelled explosive mixture to 75 the opposite ends of the explosion chamber alternately.

2. In mechanism of the class described, the combination of an explosion chamber, a hammer mounted to reciprocate therein, a 80 stem with which the hammer is connected, a piston mounted on the stem and in alignment with the hammer, a chamber in which said piston is located and within which it reciprocates, buffer heads closing the opposite 85 extremities of the piston chamber, valve mechanism located adjacent the piston chamber permitting the induction and education of the explosive mixture as the piston reciprocates, suitable means for conducting 90 the explosive mixture to the opposite extremities of the explosion chamber, and means for igniting the compressed explosive mixture in the extremities of the explosion chamber, substantially as described. 95

3. In mechanism of the class described, the combination of an explosion chamber, a hammer mounted to reciprocate therein, a tappet in alignment with the hammer and protruding into the chamber to receive the 100 blow of the latter, a stem connected with the hammer, a piston mounted on the stem and in alignment with the hammer, a chamber in which the piston reciprocates, a chamber for the explosive mixture, valves for controlling the entrance of the explosive mixture to the opposite ends of the piston chamber as the piston reciprocates, other chambers located 105 adjacent the explosive mixture chamber, valves for controlling the passage of the explosive mixture from the piston chamber to the said other chambers, the last named chambers being in communication with the explosion chamber whereby the said mixture is introduced to the explosion chamber adjacent one extremity of the hammer when the latter is at its limit of movement in either direction, and means for automatically igniting the explosive mixture in the opposite extremities of the explosion chamber. 110

4. In a rock drilling explosive engine, the combination of an explosion chamber, a hammer mounted to reciprocate therein, a tappet located to be acted on by the hammer, a stem connected with the hammer, a piston mounted on the stem and in alignment with the hammer, a chamber in which said piston reciprocates, a chamber for the explosive mixture, the said chamber communicating with the opposite extremities of the piston chamber. 115

120

125

130

ber by way of valve-controlled ports, other chambers also communicating respectively with the opposite extremities of the piston chamber by valve-controlled ports, the 5 valves of the said chambers being so arranged that as the piston valve moves in one direction the explosive mixture is drawn into one extremity of the piston chamber from the explosive mixture chamber and expelled from 10 the other extremity of the piston chamber into one of the other chambers, the said other chambers being in communication with the explosion chamber for the purpose set forth.

5. The combination of an explosion chamber 15 provided with induction and exhaust ports, a hammer mounted to reciprocate in the explosion chamber, a tappet in alignment with the hammer and arranged to be acted on thereby, means for introducing explosive 20 mixture to the explosion chamber, whereby it is compressed in the extremities of the said chamber alternately, said means including valve mechanism controlled by the reciprocation of the hammer and means for igniting 25 the explosive mixture in the opposite extremities of the chamber, whereby the hammer is reciprocated for the purpose set forth.

6. The combination of an explosion chamber 30 provided with induction and exhaust ports, a hammer mounted to reciprocate in said chamber, a drilling tool in axial alignment with the hammer, a tappet adapted to act on the tool at one extremity, while the forward extremity of the tappet protrudes

into the explosion chamber, suitable means 35 for making a fluid tight joint around the tappet to prevent the escape of explosive mixture from the explosion chamber, means for introducing explosive mixture to the explosion chamber to permit its compression in the 40 extremities of the said chamber as the hammer reciprocates, said means including valve mechanism controlled by the reciprocation of the hammer and means for igniting the explosive mixture in the opposite extremities of 45 the chamber for producing the reciprocating movement of the hammer.

7. In a motor tool, a cylinder for the combustion of gases having suitable gas inlet and exhaust openings, means for controlling the supply and exhaust to and from the cylinder, 50 said means comprising a hammer piston, means for igniting the gases within the cylinder, and an impact piece upon which the piston comes forcibly into contact. 55

8. A hammer comprising a barrel open at one end for the introduction of the part to be struck, an anvil movable in the said barrel, a hammer head for striking the said anvil, and an explosion device for imparting a reciprocating motion to the said hammer head. 60

In testimony whereof we affix our signatures in presence of two witnesses.

AUGUST B. WITTMANN.
GEORGE L. RORK.
